D. TAKAHASHI.
BUTTER CUTTER.
APPLICATION FILED DEC. 15, 1916.

Patented Sept. 18, 1917.

UNITED STATES PATENT OFFICE.

DANNOJO TAKAHASHI, OF PORTLAND, OREGON.

BUTTER-CUTTER.

1,240,387.

Specification of Letters Patent. Patented Sept. 18, 1917.

Application filed December 15, 1916. Serial No. 137,196.

To all whom it may concern:

Be it known that I, DANNOJO TAKAHASHI, a subject of the Emperor of Japan, residing at Portland, county of Multnomah, State 5 of Oregon, have invented certain new and useful Improvements in Butter-Cutters, of which the following is a specification.

My invention relates to butter cutters in general, and particularly to that class of 10 such devices as are used to cut and form butter into small cakes for individual use, such as are commonly employed in restaurants.

The object of my invention is to provide 15 a device that shall receive butter in bulk and press and cut the same into individual pieces; that is simple in construction, positive in action, easily kept clean, and cheap to manufacture.

20 I attain the above objects by means of the construction illustrated in the accompanying drawing, which therefore becomes a part of this application for Letters Patent, in which like characters of reference indicate like parts throughout the several views, and in which:

Figure 1 is a perspective view of my device partially broken away to illustrate the construction.

30 Fig. 2 is a plan view of a portion of the screw thread, shown upon an enlarged scale.

The body portion of my device which is constructed to receive the butter in bulk is constructed of a bottom 3, sides 4, and a 35 back 5.

A diaphragm 6 is placed within the body and adapted to slide longitudinally therein.

To effect the longitudinal movement of 40 said diaphragm I employ a screw 7 rotatably mounted in diaphragm 6, extending through back 5, and upon the rearward end thereof having a crank 8.

When said screw is turned in the proper direction it is caused to move forward by 45 means of a dog 9 pivotally mounted upon back 5 and having a lug 10 adapted to engage the threads upon screw 7.

When it is necessary to slide the diaphragm 6 rearwardly to receive a new 50 charge of butter the dog 9 is swung upward into the dotted position 9^a, thereby removing the lug 10 from the screw thread and enabling the screw to be withdrawn through the back 5 without turning the screw.

55 To divide the butter into proper size portions I mount upon the forward end of the

body a die frame 11 having therein a plurality of knives 12 which divide the butter as it is pressed therethrough into portions of proper size for individual use.

In order to sever these portions of butter from the main body of the butter as they are pressed through the die frame I employ a knife 13 rotatably mounted adjacent the die frame and adapted to sweep across the 65 outside face of said die frame and of the knives 12, and in contact therewith.

In order that each individual portion of the butter as it is severed by the knife 13 may be a rectangular prism it is necessary 70 that the flow of the butter through the die frame 11 shall be arrested while the knife 13 is operating across the face of the die frame, and to accomplish this it is necessary that the motion of the diaphragm 6 be arrested.

It will thus be evident that the motion of the diaphragm 6 must be intermittent and also synchronous with the motion of the knife 13.

To accomplish this I mount a gear 14 upon the rear end of shaft 15, which shaft revolves in suitable bearings 16 upon the under side of the bottom 3, and carries upon its forward end the knife 13.

A gear 17 is also mounted upon screw 7 and meshes with gear 14.

Said gear 17 is rotatably secured but longitudinally slideable upon the screw 7 by means of a key operating within a groove 80 18 upon screw 7.

A portion 19 of each screw thread is formed circumferential or normal to the axis of the screw, while the remainder 20 of the thread is helical.

As portion 19 of the thread passes lug 10 on dog 9 the screw and the diaphragm attached thereto do not advance, or in other words are longitudinally stationary, and the gear ratio of the gears 14 and 17 is such 100 that during this period of rest for the diaphragm the knife 13 sweeps the surface of the die frame 11 and severs the portions of the butter that have been pressed through the die frame by the previous motion of the 105 diaphragm.

During the remainder of each revolution of the knife 13, after the same has swept the surface of the die frame, the helical portion 20 of the thread is passing the lug 10 on dog 110 9, and thus the screw and the diaphragm attached thereto are advanced toward the die

frame 11 thus forcing the butter through said frame and past knives 12.

As a means of imprisoning the gear 17 I provide a false back 21 to the body, attached to the back 5 by spacers 22.

My invention may be made of any size and constructed of any materials deemed convenient and suitable in a device of this character, and while I have illustrated and 10 described a form of construction and arrangement of parts found desirable in materializing my invention, I wish to include in this application for Letters Patent all mechanical equivalents and substitutes that 15 may fairly be considered to come within the scope and purview of my invention as defined in the appended claims.

Having disclosed my invention so that others skilled in the art may be enabled to 20 construct and to use the same, what I claim as new and desire to secure by Letters Patent is;—

1. In a butter cutter, a body having two 25 sides, a bottom and an end piece; a die frame secured to the end of said body opposite said end piece; a longitudinally slid- 30 able diaphragm within said body; a rod rotatably attached to said diaphragm and extending through said end piece; a thread 35 upon said rod having a portion only of each circumferential turn thereof helical; a dog pivotally mounted upon said back piece and coacting with said thread; a gear ro-

tatably fixed and longitudinally slidable upon said threaded rod; a rotatable shaft 35 substantially parallel to said threaded rod; a knife mounted upon said shaft adjacent said die frame; a pinion secured to said shaft and adapted to mesh with said gear upon the threaded rod, the ratio between 40 said pinion and said gear being such that the change of pitch of the thread upon said rod holds said diaphragm stationary while said knife is performing its function; and means to operate said threaded rod. 45

2. In a butter cutter having a box like body, a die frame, a knife adjacent said die frame, and a slidable diaphragm within said body; a rod operably connected to said diaphragm; a thread upon said rod having 50 a portion only of each circumferential turn thereof helical; a dog coacting with said thread; and means whereby said knife is driven from said threaded rod in such a manner that the change of pitch of said 55 thread holds said diaphragm stationary while said knife performs its function.

In witness whereof I claim the above as my own I hereunto affix my signature in the presence of two subscribing witnesses, 60 at Portland, county of Multnomah, State of Oregon, this 25th day of Nov. 1916.

DANNOJO TAKAHASHI.
